UNITED STATES PATENT OFFICE.

JOHN OLIPHANT, OF CHICAGO, ILLINOIS, ASSIGNOR TO SULLIVAN MACHINERY COMPANY, A CORPORATION OF MASSACHUSETTS.

AIR-LIFT PUMP.

1,363,198.

Specification of Letters Patent. Patented Dec. 21, 1920.

Application filed June 28, 1917. Serial No. 177,605.

To all whom it may concern:

Be it known that I, JOHN OLIPHANT, a citizen of the United States, residing at Chicago, in the county of Cook and State of Illinois, have invented certain new and useful Improvements in Air-Lift Pumps, of which the following is a full, clear and exact specification.

My invention relates to air lift pumps.

10 It has for its object to provide an improved mixing tube for an air lift pump, whereby the air is formed into a spray and expanded before it enters the liquid in such a manner as to result in a quicker and more 15 diffused mixture. A further object of my invention is to provide an improved construction whereby the air holes in the mixing tube may be kept from clogging, the same being so constructed that they are automatically cleaned by the rush of air 20 therethrough.

In the accompanying drawings, I have shown, for purposes of illustration, one embodiment which my invention may assume 25 in practice, although it will be understood that the same is not limited to use in this form.

In these drawings,—

Figure 1 is a central sectional view of an 30 air lift pump equipped with my improvement.

Fig. 2 is an enlarged detail of a portion of the mixing tube shown in Fig. 1.

In this illustrative construction, it will be 35 noted that I have shown a standard pump installed in a well, the pump being supplied with air through a suitable down pipe 1 which in turn communicates with a riser 2 of increased diameter through a foot-piece 40 3, preferably attached to or formed integral with a suitable joint 4 inserted between different sections of the riser 2.

As shown, this foot-piece is provided with an upstanding portion 5, preferably substantially 45 conical in form and provided with an inner longitudinally disposed chamber 6, the upper end of which is closed by a cap 7 suitably attached, as by threading, to the member 5. As illustrated, a plurality of 50 openings 8 are also provided in the member 5, forming a communication between the air supply furnished to the chamber 6 and the space surrounding the member 5 and

within the riser 2. These openings 8 may, obviously, be arranged in any desired order. 55 As shown herein, they are, however, preferably arranged in a plurality of transversely disposed series spaced longitudinally of the member 5, and are provided with inclined and upwardly extending passages 9 in such 60 a manner that the air entering from the pipe 1 into the chamber 6 is discharged therefrom at an upward angle. In my improvement, it will also be noted that the mouths of these passages 9 are enlarged or 65 reamed out, as shown at 10, the same being tapered in cross section from the passage 9 toward the outlet and provided with walls 11 and 12 of different length in such a manner as to enable the air rushing through the 70 passages 9 readily to remove any sediment lodging therein.

By the use of my improved construction, it will be noted that the air which passes from the chamber 6 out through the mouths 75 10 is formed into a spray and expanded before it enters the liquid, in such a manner as to result in a more diffused mixture and also in a quicker mixing of the air and liquid adapted to expedite and facilitate the 80 upward movement of the liquid in the riser 2. Attention is also directed to the fact that through the provision of my improved construction wherein the mouths of the passages 9 are enlarged or reamed out, as 85 shown, it is possible for the passages 9 to be maintained clear, the air which rushes out through the same tending to sweep out any sediment or sand which may have settled 90 therein, as distinguished from those constructions wherein, with the passages 9 of the same diameter throughout, the sediment or sand is apt to become packed or lodged in the holes and thereby choke the same.

While I have in this application specifically described my invention as applied to a single type of tube, it will be evident that my improved means for spraying and expanding the air and cleaning the holes may be applied to various other types of pumps 100 than that shown and continue to perform its functions, it being my intention to include all such adaptations of my inventive idea within the scope of the appended claims.

What I claim as new and desire to secure 105 by Letters Patent is:

1. In an air lift pump, a mixing tube having air apertures therein provided with double bores.
2. In an air lift pump, a mixing tube having air apertures therein provided with stepped bores the outer of which constitute gradually enlarging mouths.
3. In an air lift pump, a mixing tube having air apertures therein provided with gradually enlarging mouths the walls of each mouth being disposed at an angle to the bore of the corresponding aperture.
4. In an air lift pump, a hollow mixing tube having angularly disposed outlets in its side walls provided with mouths gradually enlarged from a point intermediate the length of the outlets toward the point of discharge.
5. In an air lift pump, a hollow mixing tube having angularly disposed outlets in its side walls provided with mouths gradually enlarged from a point intermediate the length of the outlets toward the point of discharge, said mouths having walls of different lengths.
6. In an air lift pump, a mixing tube having air apertures therein provided with substantially cylindrical inlets and enlarged outlets.
7. In an air lift pump, a mixing tube having air apertures therein provided with restricted inlet portions and enlarged outlet portions the intervening bore being non-conical.
8. In an air lift pump, a mixing tube having air apertures therein, each of said apertures consisting of a restricted tube expanding abruptly adjacent its discharge to form an enlarged mouth.
9. In an air lift pump, a mixing tube having air apertures therein, each of said apertures having a substantially uniform cross sectional area throughout a part of its length, and an enlarged mouth.
10. In an air lift pump, a mixing tube having air apertures therein, each of said apertures having a substantially uniform cross sectional area throughout a part of its length, and an enlarged mouth, the walls of the latter being disposed at different angles.
11. In an air lift pump, a mixing tube having air apertures therein, each of said apertures consisting of a restricted tube having an enlarged mouth, the walls of the latter being disposed at different angles.
12. In an air lift pump, a mixing tube having air apertures therein provided with substantially cylindrical inlets and enlarged outlets, the walls of the latter being disposed at different angles.
13. A mixing tube for air lift pumps having air apertures therein, no element of whose lateral bounding surfaces is straight, the inlet ends of said air apertures being of less diameter than the discharge ends thereof.
14. A mixing tube for air lift pumps having air apertures therein so shaped that an element of their bounding surfaces is a non-straight line, the inlet ends of said air apertures being of less diameter than the discharge ends thereof.
15. A mixing tube for air lift pumps having air apertures therein so formed that if a plane be passed through the axis of an aperture and intersect the bounding wall thereof, the lines of intersection will be non-straight and will be convergent at no point between the inlet and discharge orifices of said apertures.

In testimony whereof I affix my signature.

JOHN OLIPHANT.
